UNITED STATES PATENT OFFICE.

CHARLES WEELEANS, OF TRENTON, NEW JERSEY, ASSIGNOR TO MONUMENT POTTERY COMPANY, OF TRENTON, NEW JERSEY, A CORPORATION OF NEW JERSEY.

DESIGN FOR A LAVATORY.

SPECIFICATION forming part of Design No. 36,882, dated April 19, 1904.

Application filed March 9, 1904. Serial No. 197,368. Term of patent 3½ years.

To all whom it may concern:

Be it known that I, CHARLES WEELEANS, a citizen of the United States, residing in Trenton, in the county of Mercer and State of New Jersey, have invented a new, original, and ornamental Design for a Lavatory, of which the following is a specification, reference being had to the accompanying drawings, forming a part hereof.

10 In the drawings, Figure 1 is a plan view of

the slab of the lavatory, and Fig. 2 is a front elevation of the lavatory.

What I claim as new, and desire to secure by Letters Patent, is—

The ornamental design for a lavatory as 15 herein shown.

CHARLES WEELEANS.
